BOOK END

Alfred Gilbert, London, England

Application January 30, 1936, Serial No. 61,498
In Great Britain February 8, 1935

26 Claims. (Cl. 211—43)

This invention concerns improvements in or relating to book ends in which one book end is connected to another book end (or to another member serving as a book end) by means of a flexible member, e. g., a strip or ribbon of fabric, extending between the lower parts of the book ends and in which the distance between the book ends is adjustable (so that the book ends are able to receive between them more or less books as desired) by varying the effective external length of the said flexible member, i. e. the length of that part of the flexible member disposed between the book ends.

One object of this invention is to provide book ends of the kind specified but which are relatively simple and robust in construction; whilst a further object of the invention is to make such book ends readily transportable and an underlying idea of this invention is to provide a book end such as referred to above and which includes an adjustable member adapted to have one end of the said flexible member attached thereto, said adjustable member being adjustably supported on the book end, and the latter and the adjustable member having interengaging or interlocking parts adapted when co-operating to retain the adjustable member in an adjusted position.

The adjustable member conveniently is either in the form of a winding bar, adjustment of the effective length of the flexible member being effected by rotation of this bar about its axis, or the adjustable member may comprise an anchoring bar adjustable along the book end. Alternatively a combined winding bar and anchoring bar may be employed.

The adjustable member may be adapted to be freed from the book end for adjustment purposes by a bodily movement of the adjustable member relative to the book end; such bodily movement may be a transverse movement (i. e., a movement laterally as distinct from an endwise movement), but the freeing movement may if desired be an endwise one.

In order that my invention may be clearly understood and readily carried into practice, I have appended hereto sheets of drawings, wherein:—

Figure 1 is a perspective view showing a pair of book ends constructed in accordance with this invention;

Figure 2 is an end elevation of one of the book ends shown in Fig. 1, a part of the book end being shewn broken away for illustrative purposes;

Figure 3 is a section on line 3—3, (Fig. 2);

Figure 4 is a perspective view of the winding bar employed in the book ends illustrated in Figs. 1 to 3 and 5;

Figure 5 shows the book ends illustrated in Fig. 1 collapsed for transport;

Figure 6 is an underneath perspective view of a modified form of book end constructed in accordance with this invention;

Figure 7 is an underneath perspective view of a further modified form of book end constructed in accordance with this invention;

Figure 8 is a vertical sectional elevation of a part of a book end constructed in accordance with this invention and illustrates a modification which can be applied to any of the constructions shown in Figs. 1 to 7;

Figure 9 is a perspective view of a modification of the book ends shown in Figs. 1 to 3;

Figure 10 is a sectional view of a further modification of the book end shown in Figs. 1 to 3;

Figures 11 to 16 are fragmentary views which show by way of example various possible modifications, within the scope of the present invention, to the winding bar and co-operating parts of the book end shown in Figs. 1 to 3;

In Fig. 1 of the drawings, there is illustrated a pair of book ends 1 and 2 connected together by a flexible fabric strip 3, preferably a silk ribbon of substantial width. Books 4 may be placed between the book ends and they are supported by the latter in a vertical position on end as indicated. The extent to which the book ends can separate is adjustable and is limited by the ribbon 3.

The book ends 1 and 2 are identical with one another, and each is of L-shape and comprises a foot 5 and an upright 6, and both these parts are preferably made from moulded synthetic resin.

The upright 6 is provided with a recess 7 on its inner side and the lower part of this recess is closed by a cover sheet or plate 8 secured in position by screws 9. The plate 8 is preferably recessed into the upright 6 so as to be flush with the face of the latter. The plate 8 extends to the bottom of the upright 6 but does not extend to the top of the recess 7 so that an opening or aperture 10 is left in the inner wall of the upright 6 of the book end. This aperture is extended downwardly by providing the plate 8 with a thumb or finger recess or hole 11, the purpose of which will become apparent from the subsequent description.

The recess 7, in combination with the cover plate 8, renders the lower part of the upright 6 tubular, the passage through the tubular part

being of flat rectangular cross section and of such a width and depth as to permit of the ready passage therethrough of the strip or ribbon 3.

The width of the recess 7 is restricted somewhat by a pair of inwardly extending parts 12 disposed at the sides of the recess, and the upper ends of these parts 12 constitute, with the plate 8 and the adjacent parts of the upright 6, a pair of recesses or sockets 13 of rectangular transverse cross-section into which are dropped the flat or rectangular ends 14 of a flat winding bar 15.

Preferably the end portions 14 of the bar 15 are wider than the other part of the bar and the end of the strip or ribbon 3 is clipped on to the bar 15 between the end portions 14 by a sheet metal clip 16 of inverted U-shaped cross-section.

The dimensions of the recesses 13 and the ends 14 of the bar 15 are so correlated that when the bar 15 is in the position shown in full lines in the drawings it cannot rotate about its own axis. In order to rotate the bar, and so to adjust the unrolled length of the ribbon 3, it is necessary to lift the bar 15 from the position in which it is shown in full lines and to withdraw it from the upright 6 via the opening 10 in the latter, this operation being facilitated by the provision of the thumb or finger hole 11 previously described. The process of removing the winding bar is indicated in dot and dash lines at 17 (Fig. 2).

Preferably the bar 15 is narrow and thin so that each revolution thereof only makes a small adjustment in the unrolled length of the ribbon, but greater adjustment per revolution can be had by using a wider and/or thicker winding bar. Also the recess or hole 13 is deeper from front to back than the thickness of the bar 15 to allow for the ribbon wound on to the latter.

Into the lower tubular end of the upright 6 projects an upstanding part 18 provided on the foot 5 of the book end. The part 18 is a tight fit into the upright 6 but permits of the book end readily being collapsed for packing as indicated in Fig. 5, which figure shows two book ends collapsed and packed together. From this figure, it will be seen that the parts nest nicely together, the parts 18 of the feet 5 of the two book ends extending in opposite directions.

A groove 19, having an inclined bottom, as clearly shown in Fig. 3, is provided in one face of the upstanding part 18 of the foot 5, and this groove is provided for the free passage of the ribbon or strip 3 which is laterally positioned by the side walls of said groove.

The outer face of the upright 6 is recessed upwardly as shown in Fig. 3 to ensure a snug interconnection of the foot 5 therewith so that to all appearances the foot and upright are in one piece.

Preferably the angle between the upright and the foot of each book end is left clear of obstructions so that if desired the well known form of ornamental book ends can be placed on book ends according to this invention as roughly indicated in dot and dash lines at 20, Fig. 1.

It will of course be appreciated that instead of making the winding bar 15 entirely flat, the centre part (taking the ribbon 3) could be of circular cross section so long as at least one end or part of the bar was of non-circular cross-section and co-operated with a corresponding part of the book end.

Fig. 6 illustrates a modification of the book ends shown in Figs. 1 to 3, the modification consisting in hinging the foot 5 to the upright 6 instead of making these parts separable and inter-

locking. In the construction illustrated in Fig. 6 the foot 5 is hinged to the upright 6 by two hinges 21 so arranged and operating that the upright 6 can either occupy a position at right angles to the foot 5 or lie in the same plane as the latter, this collapsed position being indicated in the drawings by dotted lines 22. When the upright 6 is in the position indicated in full lines at Fig. 6 it cannot be turned further in the direction of the arrow because of its abutment at its lower end with the foot 5 which forms a stop. When the upright lies flat as indicated by dotted lines 22 the book end is very convenient for packing.

Fig. 7 shows a further modification of the book end illustrated in Figs. 1 to 3. The book end shown in Fig. 7 has the foot 5 interlocking with the upright 6 but this is effected without the aid of the upstanding part 18 of the construction illustrated in Figs. 1 to 3.

The foot in the construction shown in Fig. 7 has a pair of projections 23 engaging in corresponding recesses 24 formed in the lower end of the upright 6 when the latter is in the upstanding position shown in the drawings, the parts being retained in this position by locking pins, screws, or the like 25 25 passing through the projections 23 and into the upright 6. The upright 6 and foot 5 are completely separable by removing the pins 25 and can consequently be packed neatly and readily for transport or storage. 30

In Fig. 8 is illustrated a modification applicable to any of the book ends according to this invention and described above, but is especially useful in the case of relatively large size book ends where a relatively wide winding bar 15 is used 35 and adjustment by rotating this may be in some cases too coarse. The object of this modification is to provide an intermediate or finer adjustment than that provided for by rotation of the winding bar. 40

For this purpose one of the walls, the inner wall in the construction illustrated in Fig. 8, of the upright of the book end is provided with one or more pairs of steps 26. The steps of each pair are disposed so that one is adapted to support one end 14 45 of the winding bar 15 whilst the other is adapted similarly to support the other end 14 of the winding bar. As will readily be appreciated from the drawings a relatively fine adjustment of the effective length of the ribbon 3 can be made simply 50 by lifting the winding bar up one step in the upright 6, for example to the position indicated by chain dotted lines 27 in Fig. 8.

Fig. 9 shows in perspective a modification of the book ends shown in Figs. 1 to 3, this modification consisting of providing the book ends each with a door 32 hinged to the upright of the book end and opening outwardly. This door gives access to the interior of the upright and the winding bar so that adjustment of the ribbon 3 can 60 be made without the necessity of removing books from between the book ends. If there is no play or slackness in the ribbon, it may be necessary to remove one or more books so as to provide the small amount of loose ribbon required to enable 65 the bar 15 to be lifted for winding up or unwinding the ribbon. In this instance the inner side of the book end is entirely closed. A ball catch or other suitable means can be provided normally to retain the door 32 closed. 70

Fig. 10 shows a similar arrangement to that illustrated in Fig. 9 but instead of the door 32 being hinged it simply lifts off the book end and is retained in its normal position at the bottom by engaging in a recess 60 in the foot 5 and at the 75

top by having a fastening, as a hooked member 61 engaging a co-operating member, e.g., a bar 62 on the upright proper. A thumb recess 63 or other device may be provided to facilitate removal 5 of the door 32.

In the construction illustrated in Fig. 11 the winding bar has its ends 28 of polygonal (e.g., octagonal) transverse cross-section instead of flat, so that the ends have a plurality of faces 29 which can alternatively cooperate with the inner 10 flat surfaces 30 and 31 of the outer and inner walls of the upright of the book end to prevent the unintentional rotation of the winding bar. The more faces 29 that are provided on the ends 15 28 of the winding bar the greater the fineness of adjustment of the ribbon 3 that can be obtained.

Instead of making the ends of the winding bar of polygonal cross-section the same object can be achieved by constructing the winding bar and 20 book end so that the one has a groove or grooves engageable by a projection or projections on the other part. In the example shown in Fig. 12, the ends of the winding bar are cylindrical as shown at 34 and the extremities of the bar are 25 provided with diametrical grooves or passages 35 whilst the upright of the book end is internally provided with a web or rib 36 for each grooved end of the winding bar, such web or rib being adapted releasably to engage in a groove 35 of 30 the winding bar so as to prevent its unintentional rotation. By providing several crossing grooves 35 in each end of the winding bar a relatively fine adjustment of the ribbon 3 can be made as will readily be appreciated.

35 A further alternative is shown in Fig. 13 where the projections 36 of Fig. 12 are replaced by pins or the equivalent 37 projecting up from the bottom of the sockets 13, one pin being arranged in each socket. The ends 38 of the winding bar are 40 in this case each provided with one or more diametrical bores or passages 39 which replace the grooves 35 of the construction shown in Fig. 12. If a plurality of passages 39 are provided they are arranged to cross one another to give a plurality 45 of winding bar positions and consequently the possibility of relatively fine adjustments of the ribbon 3. The passages 39 need not extend completely through the winding bar as shown.

Fig. 14 shows a construction employing recesses 40 provided in the upright of the book 50 end each for the reception of a pin or tooth, or any one of a number of teeth or pins 41 provided on the winding bar. A plurality of teeth or pins 41 are shown in the drawings and are provided 55 on each end of the winding bar, the teeth or pins being peripherally spaced around these ends.

Fig. 15 shows an arrangement in which the winding bar is prevented from rotation by providing each of its ends 43 with a radial pin 44 projecting outwardly therefrom and adapted to engage an abutment 45 (which may merely be a part of the book end as shown) to prevent unintentional rotation of the winding bar.

Fig. 16 shows an extension of the idea shown 65 in Fig. 14, the pins 41 of the winding bar shown in the latter figure being replaced in Fig. 16 by ratchet teeth 66 provided peripherally around one end of the winding bar. With these ratchet teeth co-operates a gravity actuated pawl 67 pivoted at 70 68 to the book end and having a finger piece 69 by which it can be disengaged from the ratchet to free the winding bar. Access to the pawl and winding bar may be had by providing the book end with a door such as for example either of 75 those respectively shown in Figs. 9 and 10. The

end 70 of the winding bar may be of plain cylindrical form and a close but rotatable fit in the socket 13. However, if desired, the ratchet and pawl mechanism may be provided at both ends of the winding bar instead of at only one end thereof. It will be seen that the winding bar shown in the drawings is capable of being rotated to wind up the ribbon 3 irrespective of the pawl 67 but the ribbon cannot be unrolled without the pawl first being disengaged from the winding bar.

In each of the constructions shown in Figs. 11 to 16 the ribbon engaging or centre part of the winding bar can be flat or cylindrical. If cylindrical it may have a longitudinal slot 46 to receive 15 the end of the ribbon.

In spite of the fact that it is preferred to use two exactly similar book ends in accordance with this invention as a pair, this is not essential as one end of the ribbon 3 could be fixed to one book 20 end or to some other structure instead of being adjustably attached to a book end.

Although it is preferred to make book ends described above from synthetic resin mouldings, the book ends may be made partly or wholly of wood 25 or metal and it is possible for other materials to be introduced in the construction of the book ends, as for example, glass and mirror glass.

Book ends constructed in accordance with the present invention have not the annoying trait 30 of separating accidentally which is common in the ornamental and other unconnected book ends; they also have the advantage of being readily adjusted to or from one another, and are simple and effective in construction, whilst at the 35 same time being of neat and compact appearance. Furthermore, they enable the ornamental effect of existing ornamental book ends to be retained if desired by mounting the ornamental book ends on book ends according to this invention as described above. In addition, they are readily and conveniently packed for storage or transit and when so packed occupy very little 40 space.

While I have described and shown certain at 45 present preferred embodiments of my invention it is to be distinctly understood that the invention is not limited to such embodiments but may be otherwise embodied within the scope of the following claims.

What I claim is:

1. In a pair of book ends adjustably connected together by a flexible strip, a winding bar rotatable about its own axis and to which one end of the flexible strip is attached, supporting means 55 on one of said book ends adapted non-rotatably to support said winding bar, and the winding bar being releasable, by a movement transverse to its own axis from such supporting means for adjustment of said flexible strip.

2. A book end adapted to form one of a pair of book ends adjustably connected together by a flexible strip, such book end having a winding bar adapted to have one end of said flexible strip attached thereto, and means on said book end for supporting the said winding bar thereon, the winding bar having a perimetrically non-circular part and the book end including therewithin a part adapted to coact with said non-circular part of the winding bar normally to prevent rotation of the latter about its longitudinal axis but the winding bar being capable of being freed for rotation by a relative movement of the winding bar and the coacting part of the supporting means, 75

such relative movement being in a direction transverse to the axis of the winding bar.

3. A book end adapted to be connected to another member by a flexible adjustable connection strip, said book end including a winding bar adapted to have one end of said flexible strip attached thereto and having a non-circular part, and the book end having a supporting part adapted removably to carry said winding bar, 10 such supporting part including a non-circular recess adapted to receive the non-circular part of said winding bar in a non-rotatable manner.

4. A book end adapted to be connected adjustably to another member by a flexible connection strip the effective length of which is variable, said book end including a winding bar adapted to have one end of the said flexible connection strip attached thereto, and said book end having supporting means for the winding bar which supporting means has a part adapted positively to interlock with a part of the winding bar normally to prevent rotation of the latter about its axis and said interlocking parts being adapted for release from one another by the movement 25 of one of the parts relative to the other in a direction transverse to the axis of the winding bar.

5. A book end adapted to be connected adjustably to another member by a flexible connection member, said book end including a winding reel adapted for connection to one end of said flexible member, and the book end having supporting means adapted to hold said reel, the latter being adapted for rotation relative to the book end to 30 wind or unwind said flexible member, and said reel having at the periphery of an end portion thereof a non-circular part or parts and the book end having a co-operatively formed part or parts co-operatively formed to prevent rotation of the 35 reel when the supporting means and reel are interengaged.

6. A book end adapted to be connected adjustably to another member by a flexible connection strip, said book end including a winding bar adapted for attachment to one end of the connection strip, and supporting means on the book end adapted to carry said winding bar, radially disposed abutment means on the winding bar and interengaging abutment means on the said 45 supporting means adapted together to retain the winding bar against unintentional rotation, and said abutment means being capable of disengagement from one another by relative movement thereof transversely of the axis of the winding 50 bar.

7. A book end adapted to be connected adjustably to another member by a flexible connection member, said book end including a winding bar having rectangular ends and adapted for attachment to one end of said connection member, and the book end also having a pair of spaced non-circular recesses adapted to receive said rectangular ends of the winding bar and in which recesses said rectangular ends of the winding bar 60 are non-rotatable about the axis of the bar.

8. A book end adapted to be connected adjustably to another member by a flexible connection member, said book end comprising a foot, an upright mounted on and collapsibly associated 65 with said foot and having a passage-way for said flexible connection member extending therealong, a winding bar adapted for connection to one end of said flexible connection member, supporting means within said book end adapted non-rotatably to support said winding bar, and the latter 70

being disengageable from the supporting means when desired for adjustment purposes.

9. A book end adapted to be connected adjustably to another member by a flexible connection member, said book end comprising a foot and 5 an upright mounted on and collapsibly associated with said foot and the upright having a passage-way for said flexible connection member extending therealong, a winding bar adapted to be connected to one end of said flexible connection member and adapted for rotation about its own axis, said bar having a perimetrical non-circular portion and said book end having a co-operating part adapted to interengage therewith releasably to retain the winding bar in an adjusted condition. 10 15

10. A book end adapted to be connected adjustably to another member by a flexible connection member, said book end comprising a foot and an upright, the foot and the upright being 20 separable and the one having a part adapted to socket into the other, a winding bar adapted for connection to one end of said flexible connection member and having a non-circular end adapted to be supported non-rotatably (but removably) in a co-operating non-circular socket 25 provided in the upright of the book end.

11. A book end adapted to be connected adjustably to another member by a flexible connection member and comprising a foot and an upright hinged together, stop means for limiting the hinging movement of the upright and foot relatively to one another in one direction, said upright having a passage-way for 30 said flexible connection member, and an adjusting bar being provided and adjustably mounted in said upright, this adjusting bar being adapted for connection to one end of said flexible connection member, and cooperating means being 35 respectively provided at the periphery of the winding bar and in the upright for releasably retaining said adjusting bar in a rotationally adjusted position.

12. A book end adapted to be connected to another member adjustably in relation thereto by 45 means of a flexible member, said book end including an adjusting reel adapted to be connected to one end of said flexible member, and supporting sockets adapted to carry the ends of said adjusting reel, the latter and the supporting sockets being formed for interengagement with one another to retain the adjusting reel in a rotationally adjusted position, and the adjustment reel being adapted for release from the supporting means by a transverse bodily movement to permit of its adjustment and consequently the adjustment of the effective length of said flexible member. 50 55

13. A book end adapted to be connected adjustably to another member by a flexible connection strip, said book end comprising a foot and a partially tubular upright, the upright mounted thereon and foot being separable and collapsible for storage, a winding bar housed within said upright and adapted for connection 60 to one end of said flexible strip so that the latter can be wound on to the bar, said upright having sockets and said winding bar having end parts non-rotatably engageable with said sockets. 65 70

14. A book end according to claim 13 wherein the ends of said winding bar are flat and said sockets are of rectangular transverse cross-section. 75

15. A book end according to claim 13 wherein 75

- said upright is apertured to give access to said winding bar.
16. A book end adapted to be connected adjustably to another member by a strip of flexible material, said book end having an upright book supporting side and a foot forming side, a winding bar adapted to be attached to one end of said flexible strip and on to which the latter may be wound, said winding bar having ends of angled transverse section and the book end having sockets removably to support the ends of said winding bar, these sockets each having a transverse section adapted to enable the ends of the winding bar non-rotatably to be interengaged therewith.
17. In combination a pair of book ends of L shape and a flexible ribbon connecting the book ends together, each book end having an upright part and a foot part connected together for collapsing at will and each book end including a reel attached to the adjacent end of said ribbon, the book end having sockets adapted removably to carry said reel and from which the latter can be lifted by a movement transverse to its own axis, and the ends of the reel having means co-operating with means on the book end releasably to lock the reel against rotation about its own axis.
18. A book end adapted to be connected adjustably to another member by a flexible strip and including an adjustable member adapted to have one end of said flexible strip attached thereto, means adjustably to support said adjustable member, and means on the book end and means on the adjustable member adapted for interlocking engagement with one another to retain the adjustable member in adjusted position, and the adjustable member being adapted for release from said interlocking engagement by a bodily movement of the adjustable member transverse to its own axis and relative to its book end.
19. A book end adapted to be connected adjustably to another member by a flexible strip, including a rotatable winding bar attached to one end of the said strip, means for supporting said winding bar rotatably on the book end, and pawl and ratchet means respectively carried by the book end and the winding bar and adapted releasably to lock the winding bar against rotation in one direction.
20. A book end adapted to form one of a pair of book ends connected adjustably together by a flexible strip or member, such book end including a winding bar and supporting means for the latter, the winding bar and supporting means being so co-operatingly formed that when interengaged the winding bar is non-rotatable relative to the supporting means, but the winding bar being capable of ready transverse bodily movement to disengage it from the supporting means to free the winding bar for rotation about its axis for adjustment of the flexible strip or member.
21. A book end adapted to be connected ad-
- justably to another member by a flexible connection strip the effective length of which is variable, said book end including a winding bar adapted for attachment to one end of said strip and rotatable about its own axis to adjust the effective length of the strip, supporting means in the book end for the winding bar and means on the book end and the winding bar adapted normally to prevent rotation of the latter about its axis but capable of disengagement (to free the winding bar for rotation) by movement of the one relative to the other transversely of the axis of the winding bar.
22. A book end adapted to be connected adjustably to another member by a flexible connection strip, said book end comprising a foot and an upright mounted on and collapsibly associated therewith, a winding bar within the upright and adapted for connection to one end of said strip, this winding bar having a flat end portion and the upright including a rectangular socket adapted non-rotatably to receive said flat end portion of the winding bar.
23. A book end adapted to be connected adjustably to another member by a strip of flexible material, said book end comprising an adjustment bar adapted to be connected to one end of said strip and on to which the latter may be wound, the said adjustment member and the book end having co-operating means to retain the adjustment member in rotationally adjusted positions in the book end, and said bar being also adapted to be shifted bodily transversely in respect to the book end to release it for adjustment of the effective external length of said strip.
24. A book end according to claim 2 having an upright and a foot part, said winding bar being disposed in the upright and the latter having a door giving access to the winding bar.
25. A book end adapted to be connected adjustably to another member by a strip of flexible material, such book end comprising an upright portion and a foot portion and having in the upright a winding reel rotatable about its own axis and adapted to be attached to one end of said flexible strip, said upright being partially tubular for the passage of said strip to said reel and having supporting means for the reel, and means within the upright and further means on the adjustment reel adapted positively to interlock together so as normally to lock releasably the adjustment member in a rotationally adjusted position in the upright.
26. A pair of book ends each comprising a foot part, an upright part, a flexible strip connecting the book ends together, a winding bar adapted for attachment to one end of the flexible strip, such winding bar being non-rotatably mounted in the upright but being movable transversely to its axis to free it for rotation and adjustment of said strip.

ALFRED GILBERT.
